UNITED STATES PATENT OFFICE.

RALPH C. DAVIS, OF BROCKTON, MASSACHUSETTS, ASSIGNOR OF ONE-HALF TO JOHN J. MORIARTY, OF BOSTON, MASSACHUSETTS.

CARD INDEX.

Application filed October 24, 1924. Serial No. 745,682.

The present invention relates to an improvement in card indexes. The object of the invention is to provide a card index of simple, compact type, easily manipulated, with immediate accessibility to any card, and which will possess among others the following advantages: retention of a large number of cards in stack in properly aligned position with precise overlap, a visible index for all the cards, access to both sides of the cards, permitted withdrawal of any card from the stack without disturbing its card holder or other cards in the stack or their respective holders, permitted withdrawal of card holders and cards from the stack at any point without disturbing other holders or cards carried by them, and permitted addition of a card and its holder to the stack at any point in the stack. It is my further object to provide each card with a card holder of improved type; also, an improved type of support for the various card holders with improved manner of securing the card holders to their common support.

The invention can best be seen and understood by reference to the drawings showing an embodiment thereof and in which—

Figure 1 is a front elevation of the card index.

Fig. 2 is a section on the line 2—2 of Fig. 1.

Fig. 3 is a section on the line 3—3 of Fig. 1.

Fig. 4 is a front elevation of the lower portion of the panel or backing with attached support for the card holders.

Fig. 5 is a perspective of one of the card holders.

Fig. 6 is also a perspective of one of the card holders showing the reverse side of the holder to that shown in Fig. 5, and

Fig. 7 is a cross section of one of the card holders with attached card.

Figs. 8 and 9 are cross sections of details of construction pertaining to the retention of the cards within their respective holders and to which reference will hereinafter be made.

Referring to the drawings:—

1 represents a backing or panel. This is preferably provided along its sides with forwardly extending flanges 2.

Upon the panel are arranged a series of

cards 3. These cards are arranged to overlap one another whereby the outer end portions of all the cards adjacent their outer edges are exposed, thereby providing for a visible index of all the cards.

4 are the card holders. These holders function also as spacing members for the cards as will later be explained.

5 is the support for the card holders. This support is fastened to the backing or panel 1 and the several card holders are attached to it.

The cards 3 present no special characteristics and are like those commonly employed in indexes of similar type. Each card, however, at a point removed from its inner edge is provided with a hinge portion 6 on which the body portion 7 of the card lying forward of the hinge portion may turn leaving the inner portion 8 of the card between the hinge portion and the inner edge of the card, fitting within and retained by a card holder 4, the body portion 7 of the card thus being capable of turning relatively to the inner portion 8 thereof and also to the card holder within which the inner portion 8 of the card is contained.

The hinge 6 may be provided in any suitable manner as by weakening the card at this point by a line of perforations 9. I prefer, however, even when perforations are employed to form the hinge, to reinforce the card on either side immediately adjacent the hinge with some strong flexible paper or material 10 (see Fig. 8), or when this reinforcement is provided, the portions 7 and 8 of the card may be severed and united by the reinforcement 10 which will then form the hinge between the two portions or sections of the card (see Fig. 9).

Each of the holders 4 consists of a narrow elongated casing of metal within which the portion 8 of the card is contained. It comprises spaced sides 11 and 12, respectively, and a connecting integral edge portion 13. Along the opposite edge of the casing the side 12 is provided with a flange 14 which extends by the edge 16 of the side 11 leaving a space 17 between the flange and the edge 16 of the side. The flange 14 presents an edge 18 and the extension of the flange is such that the edge 18 will lie about flush with the outer face or surface of the side 11.

Thus formed the holder 4 provides within it a housing within which the inner portion

8 of the card is contained and from which the card projects outwardly through the opening 17 with extension over the edge 18 which effects a bend therein.

5 The card is applied to the holder by sliding it in laterally from either side of the holder. The extension of the holder is such that when the card is properly positioned within it, the holder will preferably extend 10 for some appreciable distance on either side of the centre of the card. While the card may be slid into and out of the holder from either end by lateral movement, the card when positioned in the holder is retained 15 against withdrawal or displacement in a vertical direction by the flange 14 over the edge 18 of which the card extends. In such case vertical withdrawal or displacement of the card is prevented by the engagement 20 of the top edge of the portion 8 of the card with the flange 14 along an edge 8' removed from the inner edge of the card (see Fig. 8). In cross section the holder is such as will provide a housing within 25 it about equal to the cross section of the portion 8 of the card so that the projection of the card through the opening 17 and its extension over the edge 18 of the flange 14 will preferably come at about the 30 point of the hinge 6, which assists in preventing vertical withdrawal or displacement of the card from the holder. This is especially effective in a construction where the portions 7 and 8 of the card are separate 35 and the hinge connection is formed by the connecting piece or reinforcement 10. In such case the part 8 of the card will lie within the housing of the holder and the connecting piece 10 forming a part of the card 40 will pass through the opening 17 and over the edge 18. The bend for preventing vertical displacement of the card will then reside in the part 10 of the card. Vertical displacement of the card from the holder 45 will also be prevented by the engagement of the portion 8 of the card with the flange 14 of the holder along an edge 8' removed from the inner edge of the card substantially as shown in Fig. 9.

50 The card holders 4 are retained in aligned position by attachment to the support 5 fixed to the backing or panel 1. This support comprises a plate extending lengthwise the 55 backing along its centre and is of a length sufficient to retain all the holders and permit of their adjustment thereon. The support is fixed to the backing or panel by rivets 21. The support is provided with a part 22 inclined relatively to the backing and from 60 this part there extends a part 23 parallel with the backing, spaced therefrom and presenting an edge 24. From this edge the plate is bent back on itself to form a shoulder 65 lying back of the edge 24 on the under side of the support.

Each of the card holders 4 is fastened to the support 5 by a spring clip 26 struck from the side 12 of the holder. This clip, when the holder is laterally applied to the support, slips under the edge 24 thereof and 70 its adjacent part 23 and thus becomes attached to the support against displacement other than by a lateral withdrawing movement. Although the spring clip 26 tends to tightly hug the support for preventing accidental lateral displacement of the card holder, I prefer to provide the clip with an indented or bent portion 27 the end of which, when the holder is in place, will lie back 75 of the shoulder 25 on the support preventing accidental displacement of the card holder, but yielding to pressure.

When the card holders 4 are thus clipped onto the support they will lie in alignment 80 one above the other in contact with one another. Thus arranged they function as spacing members for the inner portions of the cards and impart the desired overlap to the outer end portions of the cards on which 85 may appear a visible index of all the cards.

The card holders 4 are held on the support 5 against displacement in a direction endwise of the support by the undermost one 90 of the row of card holders resting upon the stops 28 struck from the backing or panel 1, with a spring keeper 30 slidable upon the support to have bearing against the uppermost one of the row of card holders. The keeper is preferably of bent wire retaining 95 its hold on the support by frictional engagement therewith.

While the cards fit rather snugly in their 100 respective holders and frictional engagement will prevent their accidental lateral displacement, it is preferred that the cards be laterally retained on either side by the flanges 2 on the backing or panel 1.

The backing or panel 1 is preferably channelled, and it will be observed, especially by 105 reference to Fig. 3, that the support 5 for the card holders lies within this channel. The depth of the channel is preferably such that the support for the card holders will lie wholly within the channel and the card holders themselves will be held in a position 110 superposed on the backing where the side edges of the cards borne by the card holders will be supported by the backing on either side of the channel therein, the support of 115 the cards thus assisting in the support of their respective card holders.

The card holders are movable vertically 120 along the support thus enabling a holder to be inserted at any point along the line of 125 holders upon a retraction of the keeper 30 on the card-holder support. While the cards are held in alignment in their respective holders by the flanges on the sides of the backing or panel which prevents lateral displacement of the cards, arrangement is made 130

whereby the cards are otherwise retained within their respective holders from lateral displacement even when any card or cards is not receiving the lateral support afforded by the flanges on the sides of the backing or panel. For example, under some circumstances it is desirable to laterally withdraw one or more cards from the holder so as to lie outside the main line of cards. The card or cards thus withdrawn will extend beyond the flange on the side of the backing or panel and is retained from lateral displacement beyond the point of its withdrawal by means of one or more spring tongues 31 struck in from the side 12 of the card holder as may be seen by reference to Figs. 3 and 6.

The term "card" as used herein is meant to include not only a card proper but any paper or collection of papers which might be used within any one of the card holders.

Having thus fully described my invention, I claim and desire to secure by Letters Patent of the United States:—

1. In an index, the combination comprising a backing, a plurality of card holders parallelly arranged and superposed upon the backing with extension crosswise thereof, a support for the card holders fixed to the backing with extension longitudinally thereof beneath said holders, means whereby each of the card holders will be detachably secured to said support upon an application of the card holder laterally thereto and occupy positions contacting with one another, and cards carried by said holders.

2. In an index, the combination comprising a backing, a plurality of card holders parallelly arranged and superposed upon the backing with extension crosswise thereof, a support for the card holders fixed to the backing with extension longitudinally thereof beneath said holders, means whereby each of the card holders will be detachably secured to said support upon an application of the card holder laterally thereto and occupy positions contacting with one another, cards carried by said holders, and means whereby the cards will be laterally retained against displacement in positions in alignment with one another.

3. In an index, the combination comprising a backing, a plurality of card holders parallelly arranged and superposed upon the backing with extension crosswise thereof, a support for the card holders with extension longitudinally of the backing beneath said holders and comprising a plate having a portion fixed to the backing and a portion occupying an elevated position with relation thereto and presenting an edge, means whereby each of the card holders will be detachably secured to the elevated portion of said support upon an application of the holder laterally thereto, and a plurality of cards carried by said holders.

4. In an index, the combination comprising a backing, a plurality of card holders parallelly arranged and superposed upon the backing with extension crosswise thereof, a support for the card holders with extension longitudinally of the backing beneath said holders and comprising a plate having a portion fixed to the backing and a portion occupying an elevated position with relation thereto and presenting an edge with a portion turned back from said edge and presenting a shoulder, means carried by each of the card holders adapted to have engagement with the raised portion of said support and be retained by the shoulder thereon upon a lateral application of the card holder to said support, and cards carried by the holders.

5. In an index, the combination comprising a backing, a plurality of card holders parallelly arranged and superposed upon the backing with extension crosswise thereof, a support for the card holders with extension longitudinally of the backing beneath said holders, means carried by the respective card holders on the backs thereof whereby they may be attached to said support upon lateral application of said holders to said support and occupy positions contacting with one another, means for retaining a plurality of said card holders in contact with one another from longitudinal displacement along said support and comprising a keeper frictionally engaging said support but slideable thereon, and cards carried by said holders.

6. A card index having cards and holders for the cards, each of the cards having an outer body portion, an inner portion lying adjacent the inner edge of the card, and a hinge portion between said outer and inner portions of the card on which the outer portion may turn relatively to the inner portion, each of the card holders comprising a casing with connected spaced sides between which said inner portion of the card is contained, said casing having also a flange presenting an edge adjacent said hinge portion of the card and with a slot adjacent said edge and through which slot and by which edge the card extends out of said casing, said inner portion of the card having a drawing engagement with said flange along an edge removed from the inner edge of the card and substantially at said hinge portion thereof.

7. A card index having cards and holders for said cards, each of the cards having an outer body portion, an inner portion lying adjacent the inner edge of the card and a hinge portion between said outer and inner portions of the card, each of the card holders comprising a casing with connected spaced sides between which said inner portion of the card is contained, said casing having also a flange presenting an edge

1
with a slot adjacent said edge through which the card extends out of said casing, said flange being arranged whereby the edge thereof will engage said card extending out side said casing as aforesaid and effect a bend therein for preventing vertical withdrawal of the card from said casing.

- 5 8. A card index having a card with an inner portion, an outer portion and an intermediate portion on which the outer portion may be turned with relation to the inner portion, and a holder for said card from which said card extends and within which the inner portion of the card is contained, 10 said holder comprising a casing having open ends with connected spaced sides and a flange on one of said sides with extension into the plane of the other side of the casing and spaced therefrom to leave an opening 15 through which the card extends, said intermediate portion of the card occurring at a point just adjacent said flange and said inner portion of the card contained within said holder having bearing against said flange.
- 20 25 9. In an index, the combination comprising

ing a backing, a plurality of card holders parallelly arranged and superposed upon the backing with extension crosswise thereof, a support for the card holders having extension longitudinally on the backing beneath 30 said holders, each of said card holders comprising a casing having open ends with connected spaced sides between which a portion of a card is contained and from which casing the card extends, one of the sides of each card-holding casing being provided with a clip adapted to have engagement with said support for securing the card holder thereto upon its lateral application to said support.

35 10. A card index having a card and a holder for said card from which the card extends and within which a portion of the card is contained, said holder comprising a casing having an open end from which the card may be laterally withdrawn, and a spring tongue struck from the side of the casing and frictionally engaging that portion of the card contained within the casing.

40 RALPH C. DAVIS.
